CLAIM

The ornamental design for a flexible furniture, substantially
as shown and described.

DESCRIPTION

FIG. 1 is a perspective view of the flexible furniture shown
in an expanded form.

FIG. 2 is a perspective view of the flexible furniture shown
in FIG. 1, in a collapsed form.

FIG. 3 is a front view of the flexible furniture shown in FIG.
1

FIG. 4 is a top view of the flexible furniture shown in FIG.
1.

FIG. 5 is a bottom view of the flexible furniture shown in
FIG. 1; and,

FIG. 6 is a left side view of the flexible furniture shown in
FIG. 1, with the right side view being a mirror image of the
left side view.

The article is shown with a symbolic break in its length. The
appearance of any portion of the article between the break
lines forms no part of the claimed design. The broken lines
show portions of the article which form no part of the
claimed design.

1 Claim, 4 Drawing Sheets
